UNITED STATES PATENT OFFICE.

ANSON BELA AMENT, OF OAKLAND, CALIFORNIA.

DITCH-CLEANER.

1,278,555.

Specification of Letters Patent. Patented Sept. 10, 1918.

Application filed December 12, 1916. Serial No. 136,560.

To all whom it may concern:

Be it known that I, ANSON BELA AMENT, citizen of the United States, residing at Oakland, in the county of Alameda and State of California, have invented certain new and useful Improvements in Ditch-Cleaners, of which the following is a specification.

This invention is an improved ditch cleaner, constructed and arranged to be drawn through a ditch to remove the dirt, grass and other material therefrom, and to deliver the removed material at the sides of the ditch. The machine is provided at its forward end with means for engaging the end of the ditch to lift itself out of the ditch.

The improvements and advantages of the invention will appear from the following description.

20 Referring to the accompanying drawing:

Figure 1 is a longitudinal sectional view of the invention taken on line 1 of Fig. 2 showing the same in operating position in a ditch.

Fig. 2 is a plan view of the invention.

Fig. 3 is an enlarged fragmentary sectional view of the cleaning parts of the machine shown in inoperative position.

30 Fig. 4 is a view of a particular type of conveyer used on the machine for conveying certain kinds of material from the cleaning parts of the machine.

The invention includes a trough-shaped body 1, adapted to fit and travel in a ditch and which is mounted at its rear end on an axle 2, on which axle is journaled a roller 3 adapted to roll along the bottom of the ditch and carry the rear end of said body.

40 The trough is open at the bottom at its forward portion to receive a shoe 4 which is pivoted at its forward end at 5 to the forward end of the trough at a point above the bottom of the trough and is inclined downward from

45 its pivot to a plow blade 6 which blade projects forwardly and downwardly from the forward end of the bottom of the body 1.

The rear end of the shoe 4 is pivoted to one end of a pair of toggle links 7, the forward 50 ends of which are pivotally connected to a shaft 8 extending transversely of the shoe and a pair of toggle links 9 are pivoted at one end to said shaft and are connected at their other end to a rock shaft 10 extending

transversely of and journaled in the side walls of the body 1. A rotary cutter 12 is mounted on the shaft 8 and is adapted to project through a slot 13, extending centrally and longitudinally in the shoe and cuts a longitudinal slit in the material in the bottom of the ditch when the shoe is raised to permit the plow blade to plow up the material in the bottom of the ditch, whereby the layer of material passing over the plow blade is separated into two slabs. 60 An upwardly extending arm 15 is secured to the shaft 10 and to its upper end is connected the forward end of a rod 16 which extends rearwardly through a bracket 17 extending upwardly from a foot board 18 which extends across the top of the body 1 at the rear end thereof. On the rear portion of the rod 16 is provided a plurality of teeth 19 for engaging the rear face of the bracket to hold the rear end of the shoe 70 4 at different elevations, with relation to the plow blade, as shown in Fig. 1. At the sides of the plow blade are provided side cutters 20 for cutting and cleaning the material from the sides of the ditch. Inclined upwardly from the upper rear end of the plow blade at the sides thereof, are two conveyers 21, each of which comprises a trough 22, in the bottom of which travels the upper strand of an endless belt 23, which 80 travels over rollers 25 and 26 journaled in the lower and upper ends of the trough respectively, and also over a roller 27 near the upper end of the trough, the lower strand of said conveyer traveling under the trough. Pulleys 30 are secured on the ends of the shafts 31 of rollers 26 and a pair of pulleys 32 and a pulley 33 are secured on a shaft 34 journaled in bearings 35 at the rear of the body 1 at the upper edge of the side walls thereof. A belt 36 extends over the roller 3 and pulley 33, whereby said pulley and pulleys 32 are driven from said roller, and belts 37 extend over pulleys 32 and 30 for driving the rollers 26 so as to cause the upper strand of the belts 23 to travel upwardly in the troughs 22 to convey the material from the plow blade upwardly in said troughs. The inner walls of the troughs 22 converge to a point 40 above the plow blade 6 and in alinement with the rotary cutter 12 so as to guide the two slabs of material cut by the cutter 12, plow blade 6 and

side cutters 20 into the two troughs 22 respectively. A pair of delivery conveyers 45 extend outward from the sides of the conveyers 21 in a downwardly and rearwardly 5 inclined direction to deliver the material from the upper ends of the conveyers 21 over the sides of the ditch. The conveyers 45 comprise troughs 46 which communicate at their upper ends with troughs 22. An 10 endless belt 47 extends over rollers 48 and 49 journaled at the upper and lower ends of the troughs 46, the upper strand of the belt traveling in the bottom of said troughs and the lower strand traveling under the 15 troughs. The material passing from the conveyers 21 into the conveyers 45 falls on the belts 47 and the weight of the material causes the upper strand of the belt to travel downwardly by gravity and deliver the material 20 from the outer ends of the conveyers 47 over the sides of the ditch. Curved guides 50 lead from the upper end of the inner walls of the troughs 22 to the upper ends of the rear walls of the troughs 46, 25 which guide the material from the upper end of the conveyers 22 into the upper end of the conveyers 45. The lower edges of said guides rest close to the upper strand of the belts 23 and scrape the material adhering 30 to the belt into the conveyer 45. For conveying certain kinds of material upwardly from the plow blade an endless Chinese elevator 55 is used in conjunction with the conveyer belt 23, as shown in Fig. 4.

35 A crank axle 60 is journaled in bearings 61 at the top of the side walls of the body 1 above the plow blade 6, on the crank ends of which are journaled wheels 62. A rod 63 is secured to the axle midway thereof 40 by means of which the axle may be turned in its bearings to swing the wheels 62 up or down so that they may travel along the ground at the sides of the ditch when the body 1 is in the ditch, or along the ground 45 on a level with roller 3 to carry the forward end of the body 1 when the body is out of the ditch. The wheels may be locked in the latter position by swinging the rear end of the rod 63 into engagement with a lug 65 50 projecting upwardly from a seat 66 at the rear of the body 1. An eye 70 extends from the forward end of the body 1 to which is hooked by hook 71 a draft board 72 and into which extends the vertical leg of an angular bracket 73, the horizontal leg of which is pivoted at its forward end at 74 to the forward end of the draft board 72. A double tree 75 is connected to the angle portion of the bracket 73 extending above and over the 55 sides of the ditch, to which the rear mules are hitched to draw the machine.

60 A double tree 76 is connected to the forward end of the draft board 72, extending above and over the sides of the ditch, to 60 which the forward mules are hitched.

When the machine comes to the end of the ditch, the operator on the seat 56 disengages the rod 63 from the bracket 65 and pushes it forward until the rear end of shoe 4, through the medium of arm 15, shaft 10, 70 links 9, shaft 8 and links 7, is swung down upon the bottom of the ditch below the point of the plow blade 6 as shown in Fig. 3. The inclined draft board 72 and the inclined shoe 4 engaging the end of the ditch 75 lift the forward end of the machine out of the end of the ditch, whereupon the wheels 62 swing down on the ground below the forward end of the bottom of body 1. The rear end of the rod 63 is then brought 80 into engagement with the lug 65 and the wheels are locked in their supporting position. The rear roller 3 as it rolls up the end of the ditch lifts the rear end of the machine out of the ditch. By adjusting the 85 rear end of the shoe 4 at different distances from the plow blade the thickness of the slab of material cut from the bottom of the ditch may be varied.

When the machine comes to the end of 90 the ditch, the wheels 62 may be swung downwardly by the rod 63 upon the ground with sufficient pressure to lift the forward end of the body out of the end of the ditch, instead of depending upon the contact of 95 the shoes 72 and 4.

Having described my invention what I claim as new and desire to secure by Letters Patent is:

1. A ditch cleaner comprising a body, 100 means for mounting the rear end of the body, a plow blade at the forward part of the body, a shoe forward of said plow blade and having its forward end connecting to said body and its rear end spaced above the cutting edge of the plow blade, a rotary cutter, said shoe being provided with a central longitudinal slot through which said rotary cutter extends and is adapted to cut the material at the bottom of the ditch into 105 two slabs, and means for respectively conveying the slabs and delivering the same to the sides of the ditch.

2. A ditch cleaner comprising a body, 115 means for mounting the rear of the body, a plow blade at the forward part of said body, a shoe forward of said plow blade and having its forward end pivoted to the forward end of said body, a rotary cutter, said shoe being provided with a central 120 longitudinal slot, means for raising the rear end of said shoe above said plow blade to enable the plow blade to plow the ditch and to cause said cutter to project through said slot to cut the sod plowed out of the bottom of the ditch into two slabs, and means for respectively conveying the two slabs and delivering the same at the respective sides of the ditch.

3. A ditch cleaner comprising a body, 130

means for mounting the rear end of the body, a plow blade at the forward part of said body, a shoe forward of said plow blade and having its forward end pivoted to the forward end of said body, said shoe being provided with a central longitudinal slot, a

5 rotary cutter extending through said slot to cut the sod into slabs, adjusting means for raising and lowering the rear end of said shoe above and below plow blade, and means 10 for respectively conveying the two slabs and delivering the same at the sides of the ditch.

In testimony whereof I affix my signature.

ANSON BELA AMENT.
